US00D924942S

(12) **United States Design Patent** (10) **Patent No.:** **US D924,942 S**
(45) **Date of Patent:** **** Jul. 13, 2021**

(54) **TIP FOR A GROUND ENGAGING MACHINE IMPLEMENT**

(71) Applicant: **Caterpillar Inc.**, Peoria, IL (US)

(72) Inventors: **Eric Sinn**, Tremont, IL (US); **Doug Serrurier**, Morton, IL (US); **Corey Wells**, Peoria, IL (US); **Jason Jura**, Peoria, IL (US)

(73) Assignee: **Caterpillar Inc.**, Peoria, IL (US)

(**) Term: **15 Years**

(21) Appl. No.: **29/744,115**

(22) Filed: **Jul. 27, 2020**

(57) **CLAIM**

The ornamental design for a tip for a ground engaging machine implement, as shown and described.

DESCRIPTION

FIG. 1 is a perspective view of a tip for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Grayscale shading illustrates contour.

The broken lines illustrate structure or features which form no part of the claimed design.

1 Claim, 6 Drawing Sheets
